The ornamental design for a blackjack game display, as shown and described.

DESCRIPTION

FIG. 1 is a front elevation view of a blackjack game display showing our new design invention;

FIG. 2 is a top plan view thereof;

FIG. 3 is a side elevation view thereof;

FIG. 4 is rear plan view thereof;

FIG. 5 is a front elevation view thereof, showing the second transitioning image thereof;

FIG. 6 is a front elevation view thereof, showing the third transitioning image thereof;

FIG. 7 is a front elevation view thereof, showing the fourth transitioning image thereof;

FIG. 8 is a front elevation view thereof, showing the fifth transitioning image thereof;

FIG. 9 is a front elevation view thereof, showing the sixth transitioning image thereof;

FIG. 10 is a front elevation view thereof, showing the seventh transitioning image thereof;

FIG. 11 is a front elevation view thereof, showing the eighth transitioning image thereof; and,

FIG. 12 is a front elevation view thereof, showing the ninth transitioning image thereof.

The parts shown in dotted lines form no part of the invention.

The subject matter in this patent includes a process or period in which an image changes into another image. This process or period forms no part of the claimed design.
